UNITED STATES PATENT OFFICE.

EVERETT L. ABBOTT, OF SOUTH BEND, INDIANA.

CASE FOR OPERATING STOP-COCKS FOR WATER AND GAS PIPES.

SPECIFICATION forming part of Letters Patent No. 294,749, dated March 11, 1884.

Application filed September 4, 1882. (No model.)

To all whom it may concern:

Be it known that I, EVERETT L. ABBOTT, a citizen of the United States, and a resident of South Bend, in the county of St. Joseph and State of Indiana, have invented a new and useful Improvement in Cases for Operating Stop-Cocks for Gas and Water Pipes, of which the following is a full description, reference being had to the accompanying drawings, in which—
10 Figure 1 is an exterior elevation of the case; Fig. 2, a top or plan view of the cap; Fig. 3, a vertical section of the case, and Figs. 4 and 5 end and side views of the wrench.

This improvement relates to that class of 15 cases for cut-off valves of gas and water pipes which may be extended or contracted; and the object is to improve the construction and operation of such cases.

The improvements will be fully hereinafter 20 described, and pointed out in the claims.

In the drawings, A indicates the lower and exterior section; A', legs or supports; B, the upper and interior section of the case; C, cover or cap; D, a spiral swell on the lower section 25 of the casing, in which the groove is formed; E, a wrench having prongs F to operate the cap C, and a notch, G, to operate the rod a; H, a plate, stone, or other support for the lower end of the casing; I, section of a water- 30 pipe; J, cut-off; a, rod; b, interior spiral groove of the section A; c, pin on the section B; d, a flattened and twisted portion of the rod.

The section A is usually made of cast-iron, 35 while the section B is made of ordinary wrought-iron pipe; but they may both be cast, and, by the use of special tools for forming the groove in the lower section, they may also be made of wrought-iron tubing; but I prefer to 40 make the lower sections of cast-iron, and in order to avoid a great weight of metal, I cast them with a spiral swell, D, so as to give them sufficient strength for the groove b. The interior groove, b, may be wholly or partly cast 45 therein, and it is not essential or important that the groove should have the sharp angles shown, as a semicircular groove would operate well in use. This lower section, A, is provided with legs or supports A', which rest

upon the plate or stone H, and it holds the 50 section sufficiently above the pipe I to make the connection of the rod a with the valve J accessible and easy, and as the lower end of the rod a has no guide for sending it upon or connecting it with the valve J, I pin or otherwise fasten the rod and valve together, so that the valve itself keeps the lower end of the rod in position, and the fastening prevents the rod from being lifted or removed. The upper section is provided with a pin, c, 55 which pin is made to fit the groove b sufficient to hold this section in any position which may be desired, and which is within the limit of the groove b. It is not important that this pin should be made close-fitting, 60 as with the roughness of the pin and the groove, and the non-liability of the section B to rotate, especially after the earth is packed around it, it will hold the section B up or maintain its position. By this arrangement I give the section B a strong support by the use of a large 65 pin, c, and the pin being large, it is not liable to rust or give way when the sections are strongly connected together, however long they may have been buried in the earth. The cap 70 C is attached to the upper end of the section B by a screw-thread in the ordinary manner. As shown, the upper section is not as long as the lower one; but in ordinary practice it will be considerably longer than the section A. 75 The rod a is forked or provided with a groove at its lower end, which connects with the valve J, and its upper end is flattened until it is of a width nearly but not quite equal to the interior diameter of the section B. By twisting 80 this flattened portion one-half around, as shown at d, a bearing is formed, which supports the rod in a central position, so that it will always be reached and caught by the wrench or spanner E: It will be understood 85 that the rod a is to be of a sufficient length to be within the section B when that is at its highest point.

The operation of this device will be evident from its construction, and by the described 90 construction and arrangement of the parts an adjustable covering is provided, and the attached valve-rod held in its central position,

so that the rod cannot be removed or misplaced by either rust or use. I do not broadly claim a stop-box composed of an interior and an exterior cylinder, the former being vertically adjustable by a pin and a screw or spiral thread, as such has heretofore been done.

What I claim as new, and desire to secure by Letters Patent, is as follows:

to 1. The lower section, A, formed with the exterior spiral swell, D, having in its interior

the spiral groove b, in combination with the interior section, B, having the pin c, substantially as shown and described.

2. The rod a, having the twist d for keeping it in a central position, in combination with the section B, substantially as described.

EVERETT L. ABBOTT.
